AUTOMOBILE SIDE VIEW MIRROR

Charles W. Guimond, 1826 Norwood Drive,
Grosse Pointe Woods, Mich. 48236

Filed Mar. 19, 1975, Ser. No. 559,904

Term of patent 14 years

Int. Cl. D12—16

U.S. Cl. D12—187

FIG. 1

FIG. 2

FIG. 3

FIG. 4

FIG. 5

FIG. 6

FIG. 1 is a front elevational view of an automobile side view mirror showing my new design, attached to an automobile rear view mirror which has been shown in broken lines for illustrative purposes only;

FIG. 2 is a front elevational view thereof on an enlarged scale;

FIG. 3 is a top plan view of FIG. 2 it being understood that the bottom is substantially a mirror image thereof;

FIG. 4 is a rear elevational view of FIG. 2;

FIG. 5 is a left end elevational view of FIG. 2; and

FIG. 6 is a right end elevational view of FIG. 2.

I claim:

The ornamental design for an automobile side view mirror, as shown.
